UNITED STATES PATENT OFFICE.

FREDERICK KIEHLER, OF DETROIT, MICHIGAN, ASSIGNOR TO CADILLAC MOTOR CAR COMPANY, OF DETROIT, MICHIGAN, A CORPORATION OF MICHIGAN.

VEHICLE-TOP SUPPORT.

1,271,039.

Specification of Letters Patent.

Patented July 2, 1918.

Application filed July 8, 1914. Serial No. 849,633.

To all whom it may concern:

Be it known that I, FREDERICK KIEHLER, a citizen of the United States, and a resident of Detroit, in the county of Wayne and State 5 of Michigan, have invented a new and Improved Vehicle-Top Support, of which the following is a specification.

This invention relates to means for supporting the bows of vehicle tops in folded 10 position; and its object is to provide a support that may readily be secured to or detached from the body of the vehicle.

This invention consists in the details of construction shown, described and particularly pointed out in the claims.

In the drawings, Figure 1 is a side elevation of the rear upper portion of an automobile equipped with the improved top-support. Fig. 2 is a vertical transverse section 20 through the upper edge of the tonneau or body showing the fixed supporting bracket and the detachable bow-clamp or support carried thereby. Fig. 3 is a section of the fixed supporting bracket on the line 3—3 of Fig. 4. Fig. 4 is a plan view of the fixed supporting bracket. Fig. 5 is a side elevation of the fixed supporting bracket in position on the edge of the tonneau or body.

Similar reference characters refer to like 30 parts throughout the several views.

In the embodiment shown, the body, which is of any desired design, comprises a shell 2, the rear portion of the upper edge of which is reinforced by the longitudinal strip 3 and the transverse strip 4. The top 5 is mounted to swing vertically on the top-irons 6 in the usual manner.

Secured to the reinforcing strips 3 and 4, preferably by means of the screws 7, is a bracket which in ordinary use remains in 40 position upon the body. This bracket, as shown, comprises the longitudinally extending arms 9 and the upright arm 10, that engage, respectively, with the strips 3 and 45 4, and the barrel 11. The latter may have upon its outer end the flange 12, and is provided with the cylindrical opening 13, the inner end of which may be closed by the wall 14. Mounted in the inner end of the opening 13 is a compression spring 15 that may be retained in any desired manner, preferably by passing one of its ends 16 through a perforation in the wall 14 and bending it over as indicated at 17.

55 The barrel 11 is formed with a longitudi-

nal radial slot 19 which merges into a circumferential slot 20, the inner end of which extends outwardly to form a pocket 21. The cylindrical opening and slot are adapted to receive the shaft 22 and projection 23 of a 60 detachable bow-supporting member 24, the latter being secured to the fixed bracket by simply pushing the shaft and projection into the opening against the force of the spring 15, after which the shaft is given an angular 65 movement to carry the projection entirely through the circumferential slot 20. Upon releasing the detachable supporting member, the spring 15 thrusts it outwardly until the projection is received in the pocket 21, 70 whereby the shaft is prevented from rattling in the socket and from becoming accidentally detached.

In the embodiment shown, the detachable bow-supporting member constitutes a base 75 24 for a clamp-jaw 25 and a link 26, that are pivoted to the member 24 at 27 and 28, respectively, and a locking lever 29 comprising an arm 30 that is adapted to engage closely with the outer face of the clamp-jaw 80 25 when in locking position. The locking lever also comprises an arm 31, that constitutes a fulcrum and is received in a seat 32 formed on the jaw 25, and a seat 33 for a laterally turned end 34 of the link 26. It 85 will be understood that the clamping jaw 25 is swung outwardly and the link 26 upwardly to allow the bows of the top to enter, after which the end 31 of the locking lever is inserted in the seat 32. The end 30 is then 90 swung inwardly, which causes the seat 33 to swing outwardly and tension the link 26. As soon as the seat 33 passes below a line connecting the pivot 28 with the seat 32, the tension of the link causes the end 30 to 95 swing inwardly into snug engagement with the side of the clamping jaw and holds the clamp locked.

It will be understood that the member 24 may be detached from the bracket when the 100 top is elevated, thereby avoiding the unsightly appearance of the supports ordinarily used, as well as preventing tearing and soiling of clothing that comes in contact therewith, and also when the top is removed 105 from the vehicle; it will be further observed that the supporting member 24 is incapable of being removed from the body when the top is in collapsed position, in other words, it may be said to be locked to the body when the 110

top is lowered. The last named feature is of particular importance since it prevents the supporting member from becoming loosened by vibration and dropping out of the socket 5 and thus precludes any possibility of the top falling or twisting, and for the further reason that it enables the use of a connection between the body and supporting member of such nature as to allow ready removal of the latter without the use of tools on all occasions when it should be removed.

It is clear that various changes may be made in the details of construction without departing from the spirit of my invention. 15 I do not, therefore, wish to be limited otherwise than as indicated by the subjoined claims.

I claim:-

1. In combination with the body of a vehicle and a top mounted to swing in respect thereto from a raised to a collapsed position, two members, one a bracket secured to the body and the other a support for the bows of the top when in collapsed position, 25 a projection on one of the members co-acting with a slot in the other for securing the members together upon relative angular movement of one of the members in respect to the other, and resilient means tending to 30 separate the members when they are secured together, and means for preventing reverse angular movement of the angularly movable member.

2. In combination with the body of a vehicle and a top mounted to swing in respect thereto from a raised to a collapsed position, two members, one a bracket secured to the body and the other a support for the bows 25

of the top when in collapsed position, a projection on one of the members co-acting with 40 a slot in the other for securing the members together upon relative angular movement of one of the members in respect to the other, resilient means tending to separate the members when they are secured together, and means for preventing reverse angular movement of the angularly movable member, except by a force of such character as to overcome the tension of the resilient means. 45

3. In combination with a sheet metal automobile body having a longitudinal reinforcing strip along its upper side edge, a bracket attached thereto, said bracket having an arm that extends longitudinally along 50 said reinforcing strip and is secured thereto, a top mounted to swing in respect to the body from a raised to a collapsed position, a support for the bows of the top when in collapsed position, said bracket and said support constituting two members, one of the members having a slot therein and the other member having a projection received in the slot for securing the members together upon 55 relative angular movement of the support in respect to the bracket, and resilient means tending to separate the members when they are secured together.

In testimony whereof I have signed this specification in the presence of two subscribing witnesses. 70

FREDERICK KIEHLER.
